ROLLER FEEDING APPARATUS FOR FEEDING
SLIVERS TO CARDING ENGINES AND THE
LIKE

Irvin Marsden, Horsforth, Leeds, and Lewis Collins, Oldham, England, assignors to Platt Brothers and Company Limited, Oldham, England, a British company

Application October 8, 1945, Serial No. 621,006
In Great Britain October 11, 1944

5 Claims. (Cl. 19—167)

1

This invention relates to roller feeding apparatus for feeding slivers to carding engines and the like; and relates particularly but not exclusively to that type of apparatus known in the trade as the Scotch feed system; in which the rollers are mounted on a carriage adapted to be reciprocated over a travelling lattice for the purpose of laying the sliver thereon.

Scotch feed systems are well known in the textile trade, and are used for example to convey fleecy sliver by means of an overhead lattice from a breaker carding engine and feed same to a finisher carding engine, or for conveying fleecy sliver from a burr crushing machine and feeding same to a carding engine or scribbler.

Instead of passing through the nip of the carriage rollers of the Scotch feed system to the horizontal feed lattice of the carding engine, the sliver, or part of it, sometimes wraps round or becomes entangled in said rollers, due perhaps to foreign matter being present in the sliver being fed to a carding engine or the like, or due to breakage of the sliver; and unless this wrapping or entangling is quickly noticed by the operative, the feed rollers will continue to be driven, and the stresses thereby set up may result in a serious break-down, such as breakage of the rollers.

The object of the present invention is to provide a stop motion which will become operative to interrupt the drive to the carriage rollers as soon as the beforementioned circumstances arise, and before any damage can occur; and to provide also a combined mechanism which, after such interruption has taken place, operates to interrupt the main drive to the Scotch feed system and preferably also the drive to the carding engine, and thus bring the whole apparatus to rest.

According to the invention a stop motion for the rollers of a roller feeding apparatus for feeding fibrous material in sliver like form to carding engines and the like comprises a driving connection to the rollers and mechanism for disengaging the said driving connection to the said rollers, operable by a predetermined excess resistance to the rotation of the rollers for the feeding of the sliver as may be caused by the building up of the sliver on either or both of the rollers.

According to a preferred embodiment of the invention a stop motion for the carriage rollers of feeding apparatus for feeding fibrous material in sliver form to carding engines and the like, comprises a driving connection to the rollers and mechanism arranged for operation by a predetermined excess resistance to rotation of the rollers for the feeding of the sliver as may be caused by building up of the sliver on any of the said rollers, including means whereby such excess resistance causes movement of at least one of the said rollers for disengagement of the said driving connection to the rollers.

2

Preferably, the carriage rollers are geared together and are driven by a gear train from the driving shaft of the feeding apparatus, said rollers being journaled in a pivoted housing which is capable of tilting against the action of a spring when the normal resistance to drive of the rollers is exceeded; said tilting movement moving or lifting the gear wheel of one of the carriage rollers out of mesh with the gear train to interrupt the drive to the said rollers. The invention in such construction also includes combined mechanism, which after the tilting of the carriage roller housing has taken place, is operated upon to shift the driving belt of the Scotch feed system from the fast to the loose pulley. Further, where the carding engine being fed is driven by an electric motor, switch mechanism is provided and arranged to be operated simultaneously with the belt shifting operation to interrupt the electrical supply to said motor and bring the carding engine to rest.

In the accompanying drawings—

Figs. 1 and 2 are elevation and plan of the stop motion constructed in accordance with the invention and applied to a Scotch feed system.

Figs. 3 and 4 are elevation and plan to a larger scale of a portion of the mechanism illustrated in Figs. 1 and 2.

Fig. 5 is a diagrammatic view of the stop motion applied to a feeding apparatus known as the Apperley Feed:

In the preferred example of mechanism according to the invention as illustrated in Figs. 1 to 4 and where the carding engine being fed by the Scotch feed system is driven by an electric motor, the horizontally disposed carriage rollers 10, 11 which receive the sliver from the known overhead lattice (not shown) and feed same to the horizontal feed lattice 12 of the carding engine are mounted in bearings 13, 14 supported in a housing 15 forming part of the feed carriage 16. The feed carriage, as known, is suitably supported and mounted in guides (not shown) above the horizontal feed lattice of the carding engine, and is reciprocated across the width of said feed lattice by mechanism driven by a driving belt from a pulley on the main shaft of the carding engine in known manner.

The housing 15 in which the carriage rollers are mounted is pivoted on two stud shafts (one of which is shown in Figs. 3 and 4 and marked 17) fixed one at either side of the frame of the feed carriage 16 and mid-way of the bearings for the rollers 10, 11 in such manner that the housing is capable of pivoting or tilting on such shafts. The shafts or axles of the carriage rollers have each a gear wheel 18, 19 mounted thereon, which mesh one with the other, and gear wheel 18 rests on and meshes with the known driving pinion 20 mounted in the feed carriage 16, the driving pinion 20 and therefore the carriage rollers 10,

11 being rotated by known traversing bevel gears (not shown) as the feed carriage is reciprocated across the width of the horizontal feed lattice. The pivoted housing 15 for the carriage rollers is pressed downwards by a shaped plate spring 21 mounted on a fixed cap 22 forming part of the feed carriage, in such manner that the feed roller gear wheel 18 is normally held in mesh with the driving pinion 20. Thus the carriage rollers 10, 11 are mounted in a spring-pressed pivoted housing 15 supported by the stud shaft 17 and the driving pinion 20. When the sliver being fed begins to wrap round or become entangled with the feed rollers, the sliver trapped in the nip of said rollers forms a wedge which resists the rotation 15 of said rollers by the driving pinion, with a resulting couple which overcomes the pressure of the plate spring 21, and the carriage roller housing 15 pivots against the action of said spring, and gear wheel 18 is lifted out of mesh with the 20 driving pinion 20, and the drive to the rollers is interrupted. The housing 15 is held in tilted position by a catch, comprising a spring-controlled sliding member 23 movably mounted on the housing and having an inclined face 24 formed thereon, and an adjustable stud 25 fixed in the cap 22 on the carriage frame 16, the arrangement being such that when the housing is tilted, the spring 26 causes the sliding member 23 to move end-on, so that the inclined face 24 makes contact with the lower extremity of the adjustable stud 25 and the housing 15 is held in tilted position. To re-set the housing after the rollers 10, 11 have been cleared of the entangled sliver, a handle 27, pivoted at 28 on the cap 22 and connected to the sliding member 23 is operated to withdraw said member so that the inclined face 24 is moved clear of the adjustable stud 25, and the housing can then fall into normal position under the action of the before-described plate spring 21.

Even though the drive to the carriage rollers 10, 11 has been interrupted, it will be obvious that the carriage 16 will continue to be reciprocated across the carding engine, and mechanism is combined which is operated after the tilting of the carriage roller housing 15 has taken place.

Such mechanism comprises a shaped adjustable bar 29 having an extension 29a and being rigidly fixed by studs 30, 30 to the underside of the pivoted housing 15 the said bar working to a system of links mounted on the operative side of the framework of the carding engine. Such system of links consists of a substantially vertical handle or lever 31 pivoted at 32 to the carding engine frame 33 so as to be capable of angular movement. The vertical handle is so disposed as to be substantially in line with the extension 29a of the bar 29 mounted on the feed carriage, and said handle has an angle bracket 34 mounted thereon in such a position that the extension 29a normally passes beneath said angle bracket. About mid-way of the length of the handle is a fixed stud 35 which projects outwards at right-angles to said handle and longitudinally of the carding engine. At the outer extremity of a bracket 36 attached to the carding engine frame 33 is a pivotally mounted belt fork 37, which controls the position of the driving belt with respect to the fast and loose pulley system on the main driving shaft of the Scotch feed, and said driving belt is driven by a pulley mounted on the main shaft of the carding engine. The boss 38 of the belt fork is capable of angular movement about a stud shaft 39, and loosely fitting in a

suitable aperture in said boss and loosely embracing said stud shaft, is an upwardly inclined lever arm 40 which projects from the belt fork boss inwards towards the carding engine frame. At the free end of the inclined lever is fixed a downwardly disposed catch 41 or rectangular extension disposed approximately at right angles to the inclined lever arm, and said catch has a shaped open gap or recess 41x formed therein which embraces the stud 35 mounted on the vertical handle 31. Thus the inclined lever 40 is normally supported in position by the stud 35 on the vertical handle 31 lying in the recess 41x in the catch 41.

Two short links 42, 43, so disposed as to lie at an angle one to the other, are provided to support a pendent weight 44, and the upper extremity of the short link 42 is loosely mounted on a pivot 45 fixed to the inclined lever 40 and midway of its length, whilst the upper extremity of link 43 is pivoted on the stud 35 and disposed thereon between the handle 31 and the catch 41. The lower extremities of the two short links 42, 43 are loosely mounted on a common stud 46 fixed in the top of the pendent weight 44.

Presuming the driving belt to be on the fast pulley 47 so that the Scotch feed system is driven, then so long as the pivoted housing 15 for carriage rollers 10, 11 is in normal position, the extension 29a of the bar 29 will pass beneath the angle bracket 34 on the vertical handle 31, and the rollers will feed the sliver to the lattice 12 whilst the carriage 16 is reciprocated in known manner to lay the sliver across the width of said lattice. When the sliver begins to build-up on either of the rollers 10 or 11 the housing 15 is tilted in manner before described, and the bar 29 will be brought into operative position, and the feed carriage will continue to move across the width of the carding engine until it reaches the operative side, whereupon the extension 29a will make contact with the angle bracket 34, and the vertical handle 31 will move about its pivot 32, and the stud 35 mounted on said handle will be forced out of the shaped recess 41x in the catch 41, and the pendent weight will be free to fall by gravity and pull the lever 40 in a downward direction, so that said lever pivots about the belt fork stud shaft 39. This pivoting movement of the inclined lever 40 imparts angular motion to the belt fork 37, and the driving belt is shifted from the fast to the loose pulley 48, and the drive to the Scotch feed system is stopped. The downward movement of the lever 40 is limited by a stop 49 mounted on the belt fork bracket 36. The system of links above described are easily re-set and the belt shifted from the loose to the fast pulley by moving the vertical handle in the opposite direction.

Mounted also on the carding engine framework, is a normally closed single-pole limit switch 50, which is connected to the electric motor (not shown) driving the carding engine, and such switch is normally held in closed position by the vertical handle 31, the arrangement being such that the switch will open, on movement of said handle by the bar 29, simultaneously with the belt-shifting operation, and therefore the carding engine itself will come to rest.

Where the carding engine is one of a series, the electrical connections may be such, that if the sliver being fed to the first or any one of the series breaks, the opening of the normally closed limit switch 50 on that particular card-

ing engine will interrupt the drive to all the carding engines in the series.

Also, in addition to the stop motion mechanism above described, the carding engine may be fitted with the known electrical device which on breakage of a sliver being fed, operates an electrical circuit to ring a bell, or to operate any other audible or visual means, to attract the attention of the operative.

Further, it is to be understood that other belt shifting or knock-off mechanism of different construction from that described, whether mechanical or electrical, may be used in combination with the described means for interrupting the drive to the feed rollers.

Referring now to Fig. 5 of the drawings, the mechanism according to the invention is shown applied to an Apperley Feed system, and the feed carriage and associated parts may be identical with that described with reference to Figs. 1 to 4, the feed carriage in this case being supported on guides 51, 52 which are diagonally disposed relative to the side frames 53, 53 and the sliver is laid on a series of horizontal feed latches 54 which feed the sliver to the licker-in 55 of the carding engine.

We declare that what we claim is:

1. A stop motion for the rollers of a roller feeding apparatus for feeding fibrous material in sliver like form to carding engines and the like, comprising a driving connection to the rollers and mechanism for disengaging the said driving connection to the said rollers, operable by a predetermined excess resistance to the rotation of the rollers for the feeding of the sliver, as may be caused by the building-up of the sliver on the rollers, and further comprising a housing, bearings in the housing for the rollers, a driving gear pinion adjacent one of the rollers, gear pinions connecting the rollers, one of which is adapted to mesh with the said driving gear pinion, a pivot mounting for the said housing permitting engagement and disengagement of the said pinion with the driving gear pinion and a spring engaged with the housing to hold the said pinion yieldably in mesh with the driving gear pinion.

2. A stop motion for the rollers of a roller feeding apparatus for feeding fibrous material in sliver like form to carding engines and the like, comprising a driving connection to the rollers and mechanism for disengaging the said driving connection to the said rollers, operable by a predetermined excess resistance to the rotation of the rollers for the feeding of the sliver, as may be caused by the building-up of the sliver on the rollers, and further comprising a housing, bearings in the housing for the rollers, a driving gear pinion adjacent one of the rollers, gear pinions connecting the rollers, one of which is adapted to mesh with the said driving gear pinion, a pivot mounting for the said housing permitting engagement and disengagement of the said pinion with the driving gear pinion and a spring engaged with the housing to hold the said pinion yieldably in mesh with the driving gear pinion, and catch mechanism adapted to hold the pivoted housing in tilted position after disengagement of the driving gear pinions.

3. A stop motion for the rollers of a roller feeding apparatus for feeding fibrous material in sliver like form to carding engines and the like, comprising a driving connection to the rollers and mechanism for disengaging said rollers from the driving connection, operable by a predetermined

excess resistance to the rotation of the rollers for the feeding of the sliver, as may be caused by the building-up of the sliver on the rollers, a traversable carriage supporting the rollers, and means mounted on the carriage for operating connecting means for interrupting the traverse thereof on disengagement of the said driving connection to the rollers.

4. A stop motion for the rollers of a roller feeding apparatus for feeding fibrous material in sliver like form to carding engines and the like, comprising a driving connection to the rollers and mechanism for disengaging said rollers from the driving connection, operable by a predetermined excess resistance to the rotation of the rollers for the feeding of the sliver, as may be caused by the building-up of the sliver on the rollers, and further comprising a housing, bearings in the housing for the rollers, a driving gear pinion adjacent one of the rollers, gear pinions connecting the rollers, one of which is adapted to mesh with the said driving gear pinion, a pivot mounting for the said housing permitting engagement and disengagement of the said pinion with the driving gear pinion and a spring engaged with the housing to hold the said pinion yieldably in mesh with the driving gear pinion, a traversable carriage carrying the pivot mounting for the said housing, and means mounted on said carriage for operating connecting means for interrupting the traverse thereof on disengagement of the said driving connection to the rollers.

5. A stop motion for the rollers of a roller feeding apparatus for feeding fibrous material in sliver like form to carding engines and the like, comprising a driving connection to the rollers and mechanism for disengaging said rollers from the driving connection, operable by a predetermined excess resistance to the rotation of the rollers for the feeding of the sliver, as may be caused by the building-up of the sliver on the rollers, and further comprising a housing, bearings in the housing for the rollers, a driving gear pinion adjacent one of the rollers, gear pinions connecting the rollers, one of which is adapted to mesh with the said driving gear pinion, a pivot mounting for the said housing permitting engagement and disengagement of the said pinion with the driving gear pinion and a spring engaged with the housing to hold the said pinion yieldably in mesh with the driving gear pinion, a traversable carriage carrying the pivot mounting for the said housing, fast and loose pulleys forming part of a traverse driving means for the carriage, a bar located on the pivoted housing, and a system of weight-operated links adapted to shift the driving belt for said traverse driving means from the fast to the loose pulley, said bar being adapted to engage and operate said system on tilting of the housing.
